UNITED STATES PATENT OFFICE.

JOHN A. WRYE, OF ARGYLE, NEW YORK.

BABY SWING.

1,414,318.

Specification of Letters Patent. Patented Apr. 25, 1922.

Application filed December 3, 1920. Serial No. 427,960.

To all whom it may concern:

Be it known that I, JOHN A. WRYE, a citizen of the United States of America, residing at Argyle, in the county of Washington and State of New York, have invented new and useful Improvements in Baby Swings, of which the following is a specification.

The object of the invention is to provide 10 a simple and relatively inexpensive swing adapted for nursery and household use and designed while affording a table for the support of toys for the amusement of the occupant of the swing to effectually 15 prevent the occupant from effecting its release and thus incurring the risk of injury, the means of retaining the infant in proper position upon the seat being such, however, as to facilitate removal therefrom when the 20 apparatus is properly manipulated; and with this object in view the invention consists in a construction and combination of parts of which a preferred embodiment is shown in the drawings, wherein:—

25 Figure 1 is a perspective view of the swing.

Figure 2 is a detail view of one of the table or retainer members.

Figure 3 is a sectional view on the plane 30 indicated by the line 3—3 of Figure 1.

The device consists essentially of a base or seat 10 which may be of one piece construction, a table or retainer member 11 arranged at a suitable interval from and 35 above the seat member and held in substantial parallelism therewith by interposed spacing tubes 12 constituting standards, and looped suspending cords 13 intermediately secured to supporting rings 14 40 and terminally extending through said spacing tubes and registering openings formed respectively in the retainer and seat members and knotted as shown at 15 below the plane of the seat member.

45 The retaining or table member 11 is provided with a central opening 16 of a sufficient diameter to receive and embrace the body of the infant seated upon the base or seat member 10 and preferably comprises 50 separable elements 11^a and 11^b each of which is of an area approximately equal to one-half of that of the retaining member, separated at a point arranged for example diametrically of the opening 16, each of said 55 elements being provided with parallel arms 17 extending beyond the inner edge of the

element and provided with terminal openings 17^a which register with the cord openings in the other element, the arms of one element lying in contact with the upper surface of the other element and the arms of the second named element lying in contact with the under surface of the first named element as will be seen clearly by reference to Figure 3, to the end that in order to 60 release the occupant of the swing it is necessary to raise the outer edge for example of the element 11^a, swinging it upon a center represented by the rear ends of the arms 17 thereof and causing said outer 65 edge to follow the direction of the portions of the suspending cords which pass therethrough. When the sections or elements of the retaining member are in their normal position indicated in full lines in 70 Figures 1 and 3 they are effectually held by the tension of the cords due to the weight of the occupant, the resistance offered to movement of either of said sections or elements being sufficient to prevent 75 the child occupying the swing from effecting its release; but by exerting sufficient upward pressure upon the free or outer edge of one of the sections or elements, or in other words that section or element of which the 80 arms extend over the upper surface of the other section or element, the desired deflection may be effected to permit the child to be removed or replaced. When in the 85 normal or retaining position the sectional 90 member constitutes a convenient table or support for toys or other articles for the amusement of the occupant of the swing.

Having described the invention, what is 95 claimed as new and useful is:—

1. A swing having parallel spaced seat and retaining members and interposed spacing standards, and suspending cords extending from the upper ends of said standards and through guide openings in the upper 100 or retaining member, said retaining member being provided with an intermediate opening for the body of the occupant of the swing and consisting of sections or elements meeting on a transverse line intersecting said opening and respectively provided with arms extending beyond their inner edges in parallelism with the complementary section or member.

2. A swing having parallel seat and retaining members and tubular spacing standards interposed therebetween, and suspend-

ing cords extending through said standards and registering openings respectively in the seat and retaining members, the retaining member having an intermediate opening 5 for receiving the body of the occupant of the swing and consisting of sections or members joined on a transverse line intersecting said opening and provided respectively with arms extended beyond their 10 inner edges and provided with terminal cord receiving openings.

3. A swing having parallel seat and retaining members and interposed spacing standards, and suspending cords upon which 15 the retaining member is threaded for

movement toward and from the plane of the seat member, said retaining member having an intermediate opening for the reception of the body of the occupant of the seat member and consisting of sections or 20 elements jointed on a transverse line intersecting said opening and provided with inwardly extending arms arranged in overlapping relation with the complementary section or element, said arms being provided with terminal opening for receiving the suspending cords. 25

In testimony whereof he affixes his signature.

JOHN A. WRYE.
